BREATHABLE POLYMER COATED FABRIC

Howard L. Amberson, Madison, Wis., assignor to United States Rubber Company, New York, N.Y., a corporation of New Jersey

Application February 16, 1959, Serial No. 54,612

Term of patent 14 years

(Cl. D92—1)

Fig. 1 is a plan view of a breathable polymer coated fabric, showing my new design; and

Fig. 2 is a sectional view of the fabric of Fig. 1, taken along the line 2—2.

The design is embodied in a fabric having a surface of isolated raised portions of plastic superposed on and adhering to a base made of standard strands or threads and represented by the straight line in Fig. 2.

A complete design unit is included within the broken-line rectangle, and this unit is reproduced in regular succession throughout the length and width of the fabric.

I claim:

The ornamental design for a breathable polymer coated fabric, as shown and described.
